INVENTOR

Robt. Riale

UNITED STATES PATENT OFFICE.

ROBERT E. RIALE, OF JOHNSTOWN, PENNSYLVANIA, ASSIGNOR TO THE CAMBRIA IRON COMPANY.

BALE-TIE.

SPECIFICATION forming part of Letters Patent No. 291,228, dated January 1, 1884.

Application filed November 14, 1883. (No model.)

To all whom it may concern:

Be it known that I, ROBERT E. RIALE, a citizen of the United States, residing at Johnstown, in the county of Cambria and State of Pennsylvania, have invented certain new and useful Improvements in Bale-Ties; and I do hereby declare that the following is a full, clear, and exact description of the same.

My invention relates to that class of bale-ties composed of a buckle or fastening and a piece of wire of proper length. The objections to bale-ties made wholly of wire are that they either require manipulation to fasten them or have a positive contact at their looped or hooked ends, so that they are not adjustable to different-sized bales. The objections to the fastening devices—such as plates, buckles, &c.—used with wire in bale-ties are that they are generally difficult of manipulation, cannot be readily attached in the process of baling, and they are so costly that they have not come into general use. My invention obviates all of these defects, it is simple and inexpensive, and it is adapted to repeated use.

In the accompanying drawings, Figure 1 represents a top or plan view of my improved bale-fastening as it appears in the operation of fastening it. Fig. 2 shows a like view after it has been fastened and subjected to a strain by the expansion of the bale, and Fig. 3 is a plan view of the detached plate or buckle in one of the forms in which it may be used.

A is a plate of iron or steel, which may be nearly of the size shown in Figs. 1 and 2, or of any convenient size, which plate is provided with the longitudinal slots e e, forming the tongue F, and a hole, D.

G is the end of the wire composing the band, which is made fast to the plate A in the process of manufacture, and C is the other end of the band, adapted to be inserted in the hole D in the plate A.

In the manufacture of this bale-tie a plate of iron or steel of suitable size and shape is taken, and the slots e e and hole D are made in it by punching or otherwise. The size of the slots is graduated to the size of the plate, so that it shall be left as strong as the wire.

The size of the hole D is graduated to the size of the wire used as a band. The plate A may be either curved outwardly, as shown in Fig. 2, or it may be flat, as shown in Fig. 3. I prefer in large plates to give the top this convex form, as the linked end of the wire band at H will fit it more closely.

Having formed the plate, a piece of wire of proper size and length to form a bale-tie is taken, and one end of the wire G is passed through one of the slots e, then over the tongue F and through the other slot e, and then is returned and fastened by twisting it around the wire band, as shown, thus forming the link B around the tongue F. The plate A is thus secured to one end of the wire by the open link B, and the bale-tie as a merchantable article is complete. The method of attaching the tie to the bale is shown in Fig. 1, and consists in inserting the plain end of the wire C through the hole D and wire link B, the expansion of the bale causing the bale-tie to at once assume the form shown in Fig. 2, the end C of the wire being so effectively locked by the wire link B that it is impossible by the use of any force to shake it loose, or to cause it to strip through the hole D. This method of fastening has the further merit of so distributing the strain upon the wire that the breaking-point of the bale-tie is but little below the breaking-point of the wire.

Having thus fully described my invention, what I claim, and desire to secure by Letters Patent, is—

1. A bale-tie buckle or fastening consisting of the plate A, provided with the slots e e and hole D, substantially as described.
2. The combination, in a bale-tie, of the plate A, provided with the slots e e, and having the hole D, adapted to receive one end of the wire, with the wire link B, formed from the other end of the wire, substantially as described, and for the purpose set forth.

ROBT. E. RIALE.
